VIRGINIA

LOCOMOTIVE FEED WATER HEATER OF THE TANK TYPE

Application filed September 10, 1930. Serial No. 430,842.

This invention relates to feed water heaters particularly designed for use on locomotives, and an object of the invention is to provide a feed water heater of the tank or tender type in which the exhaust steam from the locomotive cylinders or from the auxiliaries of the engine or both are discharged into a suitable heating tank or compartment in the tender of the locomotives and in which the reserve supply of hot water will be provided.

Another object of the present invention is to provide a heater for heating water prior to its entrance into the boiler of the locomotive, which will have a low first cost, may be installed on locomotives now in use at relatively small expense, will prevent freezing of water in the tender in cold climates, thereby eliminating the necessity for the use of live steam for this purpose, and one which will result in relatively high savings in fuel in proportion to its cost of installation and maintenance.

More specifically the present invention comprises a feed water heating system for locomotives including a heated water compartment into which the water to be heated is forced by an injector from an overflow compartment. The overflow compartment has communication with the water storage compartment of the tender and receives water therefrom as well as overflow or excess water from the heated water compartment. The steam for heating the water is supplied from the exhaust of the engine cylinders and its flow into the heated water compartment is automatically controlled by a valve operated thermostatically in accordance with the temperature of the water in the heated water compartment. The heated water is delivered to the boiler of the locomotive by a pump of approved type, the exhaust of whose engine is utilized for operating the injector which delivers the water to the heated water compartment.

Other objects of this invention are to provide a feed water heating apparatus which provides a circulation of water through the heating compartment and overflow compartment thereof, thereby facilitating the heat-

ing of the water by the exhaust steam from the locomotive; for the raising of the water level in the heating compartment sufficiently to provide a head on the suction of the pump which delivers the heated water to the boiler of the locomotive even at times when the water level in the tender storage is low and also includes storage for a quantity of heated water for delivery to the boiler at times when the locomotive is not steaming.

With these objects in view, the invention consists in various features of construction and combination of parts, which will be first described in connection with the accompanying drawing, showing a feed water heater of the preferred form embodying the invention, and the features forming the invention will be specifically pointed out in the claims.

In the drawing: Fig. 1 is a side elevation of a locomotive showing the improved feed water heater applied thereto.

Fig. 2 is a view partly in side elevation, partly in section of the tender showing the feed water heater.

Referring more particularly to the drawing, the locomotive A may be of any approved type having steam cylinders B and tender C. The tender C is provided with partitions 1 and 2 therein dividing the interior of the tender into a heated water compartment 3, an overflow compartment 4 and a water supply compartment 5. The supply compartment 5 has communication with the overflow compartment 4 near the bottom thereof through a suitable opening 6 which is closed by a valve 7, the said valve being forced into closed position by the weight of water in the overflow compartment 4. Part of the steam from the cylinders B of the locomotive exhausts from the cylinders through a suitable connection 8, through the exhaust steam check valve 9, oil separator 10 and pressure reducing valve 11 through the pipe 12, and hose connection 13 into the heated water compartment 3 of the tender through the nozzle or pipe 14 of the ejector structure 15.

The nozzle or pipe 14 extends upwardly in the compartment 3 above the normal water level therein and prevents back flow of water

from the compartment into the injector structure, etc. Also the height of nozzle or pipe 14, will upon starting of the device after stoppage, induce flow or operation of the injector structure, in that the operation in the pipe will condense the steam entering the pipe to the saturation point and continued entrance of steam into the pipe will force or lift the water therein upwardly out of the pipe and induce the flow of water from the compartment 4 into the compartment 3 by the injector action.

A thermostatically operated valve 16 is interposed in the line between the cylinders B 11 and the injector 15 and it is controlled by a thermostat 17 which is positioned in the compartment 3 and is protected by a suitable mesh housing 18. The injector structure 15 includes a compartment 19 which has communication with the overflow compartment 4 and receives water from the overflow compartment which water is forced through the nozzle 20 and nozzle 14 into the heated water compartment 3 by the exhaust steam from the pump 21. The pump 21 is employed for pumping water from the heated water compartment 3 through the hose connection 22 and discharging it into the boiler of the locomotive through the usual boiler check 23. 30 The pump 21 may be of any approved type of steam operated pump, either displacement or centrifugal and in the drawing it is shown as receiving its operating steam from the boiler through the pipe connection 24. The 35 exhaust from the engine end of the pump 21 passes through the pipe 25 and the hose connection 26 into the compartment 27 of the injector structure 15. The exhaust steam passes from the compartment 27 through the 40 nozzle 28, and it picks up water from the compartment 19, forcing it through the nozzle 20 and nozzle 14.

During the passage of the water through the nozzle 14 it mixes with the exhaust steam 45 from the cylinders B of the locomotive and serves to condense the steam and heat the water providing heated or hot water in the compartment 3. Excess water from the heated water compartment 3 overflows over the partition 1 into the overflow compartment 3 and is returned to the heated water compartment through the injector structure 15. A vent 29 is provided in the partition 50 2 to permit the escape of air and vapor from the compartments 3 and 4 into the tender 5.

The compartments 3 and 4 have communication near their lower ends through an opening 30 which is normally closed by a valve 31, held closed by the pressure of water thereagainst. Suitable check valves as indicated at 32, 33 and 34 may be provided for preventing back flow of water or steam from the injector structure 15. The exhaust steam 65 from the cylinders B besides heating the

water assist in raising it into the heated water compartment 3.

Summing up, generically the operation of the improved feed water heater is as follows:—the exhaust steam from the pump 21, 70 passing through the injector structure 15 lifts or carries water from the overflow compartment 4 through the nozzle of the injector 15 into the heated water compartment 3 and during its passage through the injector structure 75 it is mixed with the exhaust steam from the cylinders B of the engine, the pressure of which is reduced by the pressure reducing valve 11, and such mixing serves to condense the steam and heat the water by the action of the steam passing through the nozzle 14 which assists in raising the water into the heated water compartment 3. The temperature of the water in the compartment 3 is controlled by the valve 16 which is operated by the thermostat 17 and controls the passage of the exhaust steam from the cylinders B into the compartment 3. The heated water is drawn off from the compartment 3 through the connection 22 by the pump 21 and delivered to the boiler of the locomotive through the boiler check 23.

As heated water is thus withdrawn from the heated water compartment 3 by the pump 21, the level of water in the compartment 3 is not lowered because of the action of the injector, but the level of the water in the overflow compartment 4 is lowered. This in turn causes the valve 7 to open and unheated water flows from the cold water storage 5 of 100 the tender "C" into the overflow compartment 4 and is lifted by the injector into the hot water compartment 3 to replace water removed therefrom by the pump 21.

While in the drawing the compartments 3 and 4 are shown as formed by partitions in the tender "C" of the locomotive, it is to be understood that these compartments may be formed independently of the tender or as a separate unit and placed in the tender without departing from the spirit of this invention.

At times, particularly in the cold climates, there is a tendency for the cold supply water in the tender "C" to freeze and to overcome this disadvantage, a pipe 40 is provided, which has one end opening into the heated water storage compartment 3 and the other end opening into the cold water storage part of the tender. The pipe 40 has a manually operable valve 41 therein, so that when it is necessary to prevent freezing of the water in the tender "C", the valve 41 may be opened, which will permit water, owing to the inclined position of the pipe 40, to flow from the heated water storage compartment 3 into the cold water storage compartment of the tender.

It will be understood that the invention is not to be limited to the specific construction or arrangement of parts shown but that these

may be modified widely within the invention defined by the claims.

What is claimed is:—

1. In a feed water heater, a locomotive tender having a heated water compartment, a cold water supply compartment, an overflow compartment between said heated water compartment and cold water supply compartment, an injector structure for injecting water and steam into said heated water compartment, said injector having connection with the overflow compartment for receiving water therefrom, the walls of said overflow compartment having valved openings therein communicating respectively with the heated water compartment and the cold water supply compartment, said valves being so constructed and arranged whereby when the water in the overflow compartment falls below a predetermined level cold water will flow from the cold water supply compartment into the overflow compartment and when water falls below a predetermined level in the heated water compartment water will flow from the overflow compartment direct into the heated water compartment. 70
2. In a feed water heater, a locomotive tender having a heated water compartment, a cold water supply compartment, an overflow compartment between said heated water compartment and cold water supply compartment, an injector structure for injecting water and steam into said heated water compartment, said injector having connection with the overflow compartment for receiving water therefrom, the walls of said overflow compartment having valved openings therein communicating respectively with the heated water compartment and the cold water supply compartment, said valves being so constructed and arranged whereby when the water in the overflow compartment falls below a predetermined level cold water will flow from the cold water supply compartment into the overflow compartment and when water falls below a predetermined level in the heated water compartment water will flow from the overflow compartment direct into the heated water compartment, and a thermostatically controlled valve for controlling the injection of steam into said heated water compartment. 75
3. In a locomotive feed water heater, in combination, steam cylinders, a water supply source, a heated water compartment, an injector, said injector including a heating steam nozzle connected to said steam cylinders and delivering exhaust steam from said cylinders to said compartment, a steam operated pump connected to said compartment for withdrawing water therefrom, said injector structure also including a water nozzle and an operating steam nozzle, said water nozzle having connection with said water supply source for delivering water therefrom to said compartment, and means controlled by temperature of water in the heated water compartment for controlling the flow of heating steam thereto. 80
4. In a locomotive feed water heater, in combination, steam cylinders, a water supply source, a heated water compartment, an injector including a heating steam nozzle connected to said steam cylinders and delivering exhaust steam from the cylinders to said compartment, a steam operated pump connected to said compartment for withdrawing water therefrom, said injector structure also including a water nozzle and an operating steam nozzle, said water nozzle having connection with said water supply source for delivering water therefrom to said compartment, said operating steam nozzle having connection with the steam exhaust of said pump whereby the exhaust steam from the pump will operate the operating steam nozzle, and means controlled by temperature of water in the heated water compartment for controlling the flow of heating steam thereto. 85
5. In a locomotive feed water heater, in combination, steam cylinders, a water supply source, a heated water compartment, an injector including a heating steam nozzle connected to said steam cylinders and delivering exhaust steam from the cylinders to said compartment, a steam operated pump connected to said compartment for withdrawing water therefrom, said injector structure also including a water nozzle and an operating steam nozzle, said water nozzle having connection with said water supply source for delivering water therefrom to said compartment, said operating steam nozzle having connection with the steam exhaust of said pump whereby the exhaust steam from the pump will operate the operating steam nozzle, and a thermostat in said heated water compartment, a valve in the connection between said cylinders and said injector, said valve connected to said thermostat whereby the injection of heating steam into the heated water compartment will be controlled by temperature of water therein. 90
6. In a locomotive feed water heater, in combination, steam cylinders, a water supply source, a heated water compartment, an injector, an overflow compartment receiving excess water from said heated water compartment, said injector structure including a water nozzle connected to said overflow compartment, a valve establishing communication between said overflow compartment and said water supply source, said valve normally maintained closed by pressure of water in the overflow compartment and operable to open when the water level in the overflow compartment falls below a predetermined level to allow water to flow from the supply 95

source into the overflow compartment, said injector structure including a heating steam nozzle having connection with said steam cylinders for delivering exhaust steam from said cylinders to said heated water compartment, and means controlled by temperature of water in the heated water compartment for controlling the flow of heating steam thereto.

7. In a locomotive feed water heater, in combination, steam cylinders, a water supply source, a heated water compartment, an injector, an overflow compartment receiving excess water from said heated water compartment, said injector structure including a water nozzle connected to said overflow compartment, a valve establishing communication between said overflow compartment and said water supply source, said valve normally maintained closed by pressure of water in the overflow compartment and operable to open when the water level in the overflow compartment falls below a predetermined level to allow water to flow from the supply source into the overflow compartment, said injector structure including a heating steam nozzle having connection with said steam cylinders for delivering exhaust steam from said cylinders to said heated water compartment, means controlled by temperature of water in

the heated water compartment for controlling the flow of heating steam thereto, a steam pump connected to said compartment for withdrawing water therefrom, said injector including an operating steam nozzle connected to the steam exhaust of said steam pump whereby the exhaust steam from the steam pump will serve to operate said operating steam nozzle.

8. In a feed water heater, a heated water compartment, an overflow compartment receiving excess water from said heated water compartment, a water supply compartment, a valve connection between said water supply compartment and overflow compartment said valve connection so constructed and arranged whereby when the water falls below a predetermined level in the overflow compartment the valve will open to permit water to flow from the water supply compartment into the overflow compartment, an injector structure for injecting steam and water into said heated water compartment, and a connection between said injector and said overflow compartment whereby the injector will receive water from said overflow compartment.

In testimony whereof I affix my signature.
